UNITED STATES PATENT OFFICE.

CHARLES L. CURTIS, OF NEW YORK, N. Y., ASSIGNOR TO FERDINAND STRAUSS, OF SAME PLACE.

HARMONICA.

SPECIFICATION forming part of Letters Patent No. 611,287, dated September 27, 1898.

Application filed April 1, 1898. Serial No. 676,036. (No model.)

To all whom it may concern:

Be it known that I, CHARLES L. CURTIS, of New York city, county and State of New York, have invented certain new and useful Im-
5 provements in Harmonicas, of which the following is a specification.

This invention relates to a harmonica of novel construction, and more particularly to novel means for attaching the covers to the body of the instrument. I form a groove in each end of the cell-block to engage an inwardly-turned flange of the cover. The cover is secured in place by being drawn from the front or back over the cell-block, with 10 its flange entering and confined within the groove. In this way a reliable connection is formed which closes the harmonica entirely at the ends and, moreover, avoids the objectionable exposed edges of the covers found in 15 those harmonicas in which the covers slide in longitudinal ways of the cell-block.

In the accompanying drawings, Figure 1 is a side elevation of my improved harmonica; Fig. 2, an end view of the same; Fig. 3, a cross-section on line 3 3, Fig. 1; Fig. 4, a rear view of the harmonica; Fig. 5, a front view thereof; Fig. 6, an enlarged cross-section showing one of the covers partly withdrawn; Fig. 7, a side view of the cell-block, showing 20 one of the reed-plates partly broken away; and Fig. 8, a perspective view of one of the covers.

The letter *a* represents the cell-block of the harmonica, carrying on each side the usual reed-plate *b*. Along each end I form in the cell-block, back of the reed-plate, a transverse groove *a'*, extending from the front to the rear of the instrument. The covers *c* have inwardly-extending or curved ends *c'*, terminating in flanges *c''*, which are adapted to be received by the grooves *a'*. At the front each cover terminates in an inwardly extending or curved nose *c³*, the edge of which is adapted to engage a longitudinal groove *b'*, formed 25 near the forward edge of the reed-plate *b*.

To the nose *c³* a spring-like action is preferably imparted, so that by snapping into its groove *b'* it will securely lock the cover in

place. To this effect I have shown the nose to be detached at its ends from the body of the cover by the diagonal incisions *c⁴*, which impart to the nose an independent spring action. 50

To secure the covers, they are slipped from the front or rear over the reed-plates, with the flanges *c²* entering the grooves *a'*, until the edge of the spring-nose *c³* snaps into its seat *b'*, when the cover will be securely held in place. In a corresponding manner the cover may be readily removed, if access to 55 the reeds is to be obtained.

It will be seen that with my improved construction the ends of the harmonica are entirely closed, Fig. 2, and that still the covers are secured to the cell-block in a removable manner. Thus the finish and beauty of the instrument are increased and the objectionable raw edges heretofore generally found on 60 removable covers are entirely obviated.

What I claim is—

1. A harmonica composed of a cell-block having transverse grooves at its ends, and of covers having flanged ends adapted to engage said grooves, substantially as specified. 70

2. A harmonica composed of a cell-block having transverse grooves at its ends, and of covers having inwardly-extending flanged ends adapted to engage said grooves, substantially as specified. 75

3. A harmonica composed of a cell-block having transverse grooves at its ends, and of covers having inwardly-extending flanged ends adapted to engage said grooves, and an inwardly-extending nose, substantially as specified. 80

4. A harmonica composed of a cell-block having transverse grooves at its ends, reed-plates having a longitudinal groove, and covers having end flanges adapted to engage the transverse grooves, and a spring-nose adapted 85 to engage the longitudinal groove, substantially as specified. 90

CHARLES L. CURTIS.
